UNITED STATES PATENT OFFICE.

EMERSON B. MOSELEY, OF ALLIANCE, OHIO, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

LEAF FOR FILING APPLIANCES.

1,162,303.

Specification of Letters Patent. Patented Nov. 30, 1915.

Original application filed January 13, 1910, Serial No. 537,965. Divided and this application filed December 31, 1914. Serial No. 879,927.

To all whom it may concern:

Be it known that I, EMERSON B. MOSELEY, a citizen of the United States, residing at Alliance, in the county of Stark and State 5 of Ohio, have invented certain new and useful Improvements in Leaves for Filing Appliances, of which the following is a specification.

This invention relates to improvements in 10 leaves for filing appliances of the type shown in my copending application, Serial No. 537,965, filed January 13, 1910, of which this application is a division, and the object 15 of the invention is to provide an improved leaf which is of simple construction and which is light and at the same time rigid and durable.

For the purpose of illustration, I have shown in the accompanying drawings a preferred embodiment of my invention, in 20 which—

Figure 1 is a detached perspective view of 25 a leaf or bill holder embodying my invention, with parts broken away to show details; Fig. 2, a detached perspective view of a dividing plate of the leaf; and Fig. 3, a fragmentary section through a portion of the leaf.

Similar numerals refer to similar parts 30 throughout the drawings.

In the preferred form of my construction the leaf is formed from two thin metallic plates 1, placed back to back. The opposite ends of the plates are bent at substantially 35 right angles in opposite directions to form the flanges 2 on the opposite sides of the leaf.

3 indicates a binding member, preferably 40 of U-shape, and extending along the opposite site bent over end flanges 2 and the lower edge of the leaf. The binding strip 3 operates as a plate to which the end flanges 2 of the plates 1 are secured, and also provides a suitable support for hinge connections, such as 4, for pivoting one leaf to another of a series.

5 and 5^a indicate strips extending from 45 end to end and mounted upon the opposite faces of each leaf. The strips 5 are arranged along the upper and lower edges on each face of the leaf, while the strip 5^a extends parallel to and preferably midway between the strips 5. It will be understood

that each strip 5 or 5^a upon one face of the leaf alines with a corresponding strip upon 55 the opposite face of the leaf, so that each two alined strips may be secured to the adjacent leaf by the same means, which may be the rivets 6.

7 indicates a series of T-shape openings or 60 apertures formed in the inner side of each of the strips 5 and in the opposite sides of the strip 5^a. It will be understood that the apertures 7 in one side of a strip aline with the apertures formed in the opposing side 65 of an adjacent strip.

8 indicates a series of dividing plates extending between and secured to the opposing walls or faces of the strips 5 and 6 upon the opposite faces of each leaf. The plates 8 70 are spaced relative to each other and the end walls of the leaf to divide each leaf into slip-receiving spaces. Each plate 8 is somewhat longer than the distance between the opposing walls of two strips 5 and 5^a, and comprises a bar or strip having lips 9 at its opposite ends and bent at right angles to the bar and in opposite direction. The ends of the bar and lips 9 are inserted into the apertures 7 and thus secure the plates 8 in position. In this form of construction it will be seen that the plates 8 and strips 5 and 5^a 75 are secured to each other in a manner that will prevent the displacement or separation thereof, and that the plates 8 cannot be disconnected from the strips 5 and 5^a by strains which may be transmitted to them intermediate their ends in a direction parallel to the strips 5 and 5^a. Each plate 8 is preferably 80 formed from a section of thin metal, doubled upon itself along a central longitudinal line 10. The doubled plate is slotted a short distance inwardly from its opposite ends along the line of fold to form the lips 9, which are bent at right angles to 85 the strip and in opposite directions, as shown in Fig. 2. The strips 5 and 5^a are preferably formed of wood, and when the nature of the wood will permit, the bent over 90 ends or lips 9 of the plates 8 may be driven 95 into the strips 5 and 5^a, as shown in Fig. 1, thus obviating the necessity of forming apertures 7 in the strips 5 and 5^a.

It will be understood that the strips 5 on opposite faces of each leaf along the free 105 edges thereof impart rigidity to the leaf,

and that the same means which secure alined strips to the leaf operate to maintain the metallic plates 1 back to back.

As the front and rear leaves of a series of 5 leaves, such as is shown in my copending application above referred to, carry or support paper slips upon one face only, it will be understood that each of these leaves is formed from a single plate 1 and only one 10 set of strips 5 and 5^a, and plates 8, are secured thereto.

I claim:

1. A leaf for a filing appliance formed from a pair of thin metallic plates placed 15 back to back, the opposite side edges of the plates being bent in opposite directions at right angles to the plates, binding strips extending along the opposite bent over ends of the plates, and means for securing the 20 said bent over ends to the binding strips.

2. A leaf for a filing appliance formed from a pair of thin metallic plates placed back to back, the opposite side edges of the plates being bent in opposite directions at 25 right angles to the plates, a U-shaped binding strip extending along the opposite bent over ends and the lower edge of the said plate, and means for securing the bent over ends of the plates to the said binding strip.

3. A leaf for a filing appliance formed from a pair of thin metallic plates placed back to back and provided with spaced 30 ribs arranged parallel to each other, and means for connecting the plates together including members extending along two opposite sides of the leaf.

4. A leaf for a filing appliance comprising a back formed from sheet metal, a pair of spaced strips mounted upon the said back 40 and each formed with a series of T-shaped apertures each adapted to aline with an aperture in the other strip, and a dividing plate provided on its opposite ends with lips extending in opposite directions at right an-

gles to the plate and arranged to enter the 45 said T-shaped apertures to secure the plate to the said strips.

5. A leaf for a filing appliance comprising a back formed from sheet metal and a pair of longitudinally extending wooden 50 strips secured to the said back, and a dividing plate extending between the opposing walls of the said strips, the said dividing plate being formed from a section of metal doubled on itself along a central longitudinal line, and the opposite ends of the doubled plate being slotted along the line of fold to form lips that are bent at right angles to the plate in opposite directions, and adapted to be driven into the said 55 wooden strips for securing the said plate in position.

6. A leaf for a filing appliance comprising a back formed from sheet metal, a pair of spaced wooden strips secured to said 60 back, and a dividing plate extending between the opposing walls of said strips, the opposite ends of said dividing plate having lips bent at right angles to and extending in opposite directions from the plate and 65 adapted to be driven into said wooden strips for securing the plate in position.

7. A leaf for a filing appliance comprising a back formed from a pair of sheet metal plates placed back to back and having 70 their opposite side edges bent at right angles in opposite directions, means for connecting the plates together including strips secured to the bent over edges of the plates, a plurality of spaced wooden strips secured to 75 opposite sides of the back, and a plurality of spaced dividing plates extending between the opposing walls of said wooden strips.

EMERSON B. MOSELEY.
